UNITED STATES PATENT OFFICE.

BENJAMIN W. HOXIE, OF HARTFORD, CONNECTICUT, ASSIGNOR TO
OWEN H. JONES, OF SAME PLACE.

VALVE.

SPECIFICATION forming part of Letters Patent No. 311,833, dated February 3, 1885.

Application filed April 7, 1884. (No model.)

To all whom it may concern:

Be it known that I, BENJAMIN W. HOXIE, of Hartford, Connecticut, have invented a new and useful Valve, of which the following description and claims constitute the specification, and which is illustrated by the accompanying sheet of drawings.

This valve has two distinguishing characteristics. First, it revolves under the action of the passing fluid in a peculiar manner; second, it indicates externally whether it is open or closed.

Figure 1 is an external side view of the apparatus. Fig. 2 is a view of the left-hand end of the same. Fig. 3 is a central longitudinal section on the line X X of Fig. 2. Fig. 4 is a central cross-section on line Z Z of Fig. 1. Fig. 5 is a side view of the perforated disk G.

A is the exterior shell. It has the openings B, C, and D, all of which have screw-threads for the reception of conduit-pipes. The cap E is screwed into the opening D in Figs. 1 and 3, leaving the opening C for the reception of the outlet-pipe and the opening B for the reception of the inlet-pipe; but the cap may be screwed into the opening C, leaving the opening D for the reception of the outlet-pipe. The shell A also has the annular valve-seat F, and is furnished with the perforated disk G, which latter is screwed into the opening D in advance of the cap E. The valve proper consists of the disk H, the inclined wings I, J, K, and L, and the stem M. The left-hand part of the stem has its surface cut into the form of a circular rack, N. The right-hand part of the stem is encircled by a spiral spring, O, which works between the annular shoulder P on the stem and the perforated disk G. The extreme right-hand end of the stem revolves in the central perforation of that disk. The rack N works the pinion Q. That pinion is keyed to the shaft R, and that shaft passes through the stuffing-box S to the exterior of the shell A. On its outside end the shaft R is provided with a pointer, T, which

oscillates on the face of the dial U, and which is protected from harm by the glass disk V, held in place by the annular gland W.

The mode of operation is as follows. Fluid passing into the apparatus from the inlet-pipe 50 forces the valve back from its seat against the action of the spring O. That backward motion is communicated to the pinion Q and shaft R, and thus to the pointer T, causing the latter to oscillate on the face of the dial U, and thus 55 to indicate the fact that the valve is open. So, also, the action of the fluid in passing through the valve causes the valve to revolve with the stem M, inasmuch as the wings I, J, K, and L are inclined, as shown in the drawings, and 60 are therefore operated upon by the passing fluid much as the floats of a windmill are operated upon by air in motion. If the cap E is screwed into the opening D, the fluid passes 65 out through the opening C; but if the cap is screwed into the latter, then the fluid passes through the four outer perforations of the disk G, and thence through the opening D. If the constructor prefers, he may omit one or the other of the last-named openings. When 70 the valve is used in the inlet-pipe of a steam-boiler or other locality where there is a sufficiently strong backward pressure of steam or other fluid to close the valve without the aid of the spring O, that spring may be omitted. 75

I disclaim the invention shown in Letters Patent of the United States No. 160,640, granted to John Bird, March 19, 1875, for an "im- 80

provement in valves for street water-mains."

I claim as my invention—

The valve H, having the stem M, provided with the rack N, in combination with the pinion Q, the shaft R, and an external indicator, substantially as described, and for the purpose set forth.

BENJAMIN W. HOXIE.
